MECHANISM FOR TREATING LEAVES

Joseph Gough, Newark, N. J., assignor to Gough
Stemming Machine Corporation, New York,
N. Y., a corporation of New Jersey

Application November 5, 1932, Serial No. 641,343

16 Claims. (Cl. 131—57)

My invention relates to machines for stemming leaves, i. e. to machines for removing more or less of the long central vein or mid-rib from the blades of leaves, such as are used for example for stemming tobacco leaves.

It provides an improved device for removing those parts of the leaf blades that the stemming operation proper is unable to remove from the stems. Further it provides for more or less separating the stems wherever a number of leaves are more or less bunched together, and for breaking up the suckers, so-called, which accompany tobacco leaves for example, and sometimes interfere with the stemming operations; and it also provides for making the said stem cleaning device, or another performing substantially the same functions, effective on stems of leaves that are more or less bunched together. Still further, it provides a device for cleaning stems that is capable of co-operating with stemming machines of the type to which the operator delivers the leaves more or less in bunches or masses.

The invention can be explained best in connection with the particular stemming machine embodying it rather diagrammatically illustrated in the accompanying drawing in which—Fig. 1 is a plan view of the machine. Fig. 2 is an elevation of the same machine. Fig. 3 is a sectional elevation about on the line III—III of Fig. 1. Fig. 4 is an elevation, partly in section, of the stem cleaner and device for separating bunched stems, of the same machine, drawn to a somewhat larger scale.

It will be understood of course that my invention is not limited to the particular machine shown in the accompanying drawing, and of this machine illustrated only substantially so much is shown as is necessary to enable the invention to be explained. Generally speaking, the stemming machine illustrated is well-known. It has a belt 1 of card clothing to carry the leaves to the stemming station and strip the blades from the leaves as the stems are grasped between a pair of driven belts 2 and 3 and thereby pulled away from the blade stripper 1 (pulled upwardly in Fig. 1). This blade stripper or card clothing belt 1 is mounted on suitable pulleys 4, 5 etc., and in a machine of the type here illustrated, is driven continuously in the direction indicated by the arrows in Fig. 2, the stems being pulled from the blades as the blades are carried past the stem-grasping belts 2 and 3. The stemmed blades are delivered at the right-hand end of the machine in Figs. 1 and 2, and the stems are thrown out to the back of the machine by the belts 2 and 3

(upwardly in Fig. 1). The upper card clothing belt 9, mounted on suitable pulleys 10, 11 etc., serves to prevent the possible escape of the blades from the stripper 1; this belt 7 may be driven positively, say through its pulley 10 or 11, or it may be driven by the engagement of its teeth with the teeth of the driven lower card clothing 66 belt 1.

To the left or at the entrance end of the machine, is a conveyor to feed the leaves to the card belts; in the present instance, this conveying mechanism has the form of a pair of chain belts 14 and 15, each provided with projecting pins 16 to positively propel the leaves along, together with a parallel belt or belts 17, which may be smooth surfaced belts to support the tip ends of the blades in transit. These belts may be mounted on any suitably disposed pulleys or sprocket wheels, and are driven in synchronism. To the latter end all of these belts may have supporting sprockets 18 and 19, or supporting pulleys 20, all keyed to a common driving shaft 21 driven, say, from the longitudinal shaft 22 which may receive its power from the same source as drives the blade stripper 1 and the stem belts 2 and 3. 65 70 75 80 85 90 95 100 105 110 Usually I drive these conveyor belts 14, 15 and 17 intermittently, i. e. step by step. In the machine illustrated, this is the function of the pawl 23, and the co-operating ratchet 24 keyed to the shaft 21; a crank 25 and link 26 enables the shaft 22 to oscillate the bracket 27 loose on the end of shaft 21 which carries the pawl 23, so that the drive shaft 21 is turned intermittently, or step by step, and thereby the conveyor belts 14, 15 and 17 advanced in the same manner. Plates 30 and 31, carried by brackets 32 and pressed downwardly therefrom by the springs 33, serve to press and hold the leaves between the propelling pins 16. At the exit end of the propelling belts 14 and 15, an inclined plate 34 rising from between these belts lifts the leaves to a position nearly above the tops of the projecting pins 16 (see Fig. 2), while an upper co-operating plate 35 helps to maintain control of the leaves. This exit end of these belts is adjacent the card clothing on pulley 10. In practice the operator tears the large bunches of leaves apart into smaller bunches or masses, each containing a few leaves, and lays these small bunches or masses on the conveyors, as is apparent from Fig. 1. The conveyors carry these masses along, step by step, and present them seriatim to the card clothing belt 9 adjacent the plates 34 and 35. This card clothing being in continuous movement, and being driven at a sufficiently high speed, snatches the leaves from these

small bunches one or two at a time, and carries them down into engagement with the stripping belt 1; a downwardly curved extension 36 of the plate 34, and parallel curved plates 37 serve to 5 guide the leaves in this downward movement, the plate extension 36 also aiding to thrust the leaves well into the grip of the teeth of the card clothing 9; wires or other guides 39 placed above the leaves and more or less curved concentric with the guide 10 plates 37 may be used to keep the leaves from rising from the guide plates. A lower curved plate 40 (see Fig. 2) together with springs 41 carried by it, serves to support the guide 36 and at the same time permit the latter to yield 15 away from the card clothing 9, as the sizes of the leaves may demand.

It will be understood of course that the mechanism so far described is already known, and that while the leaves are delivered to the left-hand 20 end of the machine, more or less bunched together (as illustrated at the left of Fig. 1) they are delivered to the stemming station more or less seriatim, as will be evident from the leaves illustrated at the right-hand end of Fig. 1.

25 As will be apparent from the leaves shown at the left hand end of Fig. 1, the blade material of the leaves extends well down toward the butt ends of the leaves. Necessarily much of this is beyond the grasp of the blade stripper 1 (or 1 and 30 9) and hence this portion of blade material would accompany the stems removed from the major part of the blades at the stemming station, except for the use of the stem cleaner and co-operating mechanism illustrated in the drawing.

35 "Butters", so-called have been employed heretofore to clean the butt ends of stems. My present stem cleaner is preferable however to any prior "butter" of which I am aware. Essentially this stem cleaner consists of a carrying body 46 and a 40 plurality of projecting more or less wire-like members 47. Necessarily (in order that the body 46 may drive the cleaning members 47), the body 46 must be made up of or incorporate a more or less rigid material, and if the wire-like projecting members 47 are mounted directly and rigidly in 45 the body 46, I have found that there is considerable tendency for these projecting members to bend or break. To avoid this, I connect the projecting members 47 to the more or less rigid body 46 in a yielding manner, so that this connection may yield to permit the wire members 47 to be 50 displaced as and when necessary to preserve them from bending or breaking; to this end, generally speaking, I make the connection between the wires 47 and the more or less rigid body 46 so yielding that at a speed somewhat less than normal this connection can yield sufficiently to permit the cleaning members 47 to pass over the stems substantially without cleaning the stems.

55 Then in order to clean the stems, I drive the rigid body 46 at such a speed as to carry the cleaning members 47 into and over the stems so rapidly that they serve to clean the stems, in part by their own momentum as it were. To form such a connection between a rigid member 46 and projecting wire-like members 47, the members 47 may be held in a flexible member or members 48, clamped to the rigid body 46 (see Figs. 3 and 4), but with the wire-like members 47 entirely outside the rigid body 46; that is to say, I may mount the wire-like members 47 in a portion of the carrying member 48 which is flexible externally of the body 46 of rigid material. Preferably the cleaner is a rotary structure; that is to say, the member 46 constitutes a hub as it were,

from which the flexible carriers 48 project more or less spoke-like, and from which carrying members 48 the wire-like cleaning members 47 project more or less spoke-like also. The flexible projecting members 48, while affording a quite yielding connection between the wire-like members 47 and the rigid material 46, can properly be made stiff enough to hold the members 47 straight out, spokelike, when the device is at rest. Each projecting member 48 may consist of a strip of rubber, or canvass-backed rubber, etc.; this may be folded on itself and perforated at the crease for the passage of the projecting wire-like members 47, the latter being formed together in pairs, the legs of each U-shaped pair projecting through these holes in the crease while each cross piece of the U is contained within the fold of the material; conveniently the folded member can be stood in recesses in the hub 46 and therein fastened by clamping members 49 held to the hub by screw bolts 50 for example, all as will be apparent from Figs. 3 and 4. This rotary cleaning structure may be rotated at adequate speed to have the centrifugal forces of the wire-like members 47 co-operate in the cleaning of the stems 100 in the manner before indicated, by means of its attached sprocket wheel 51 and driving chain 52, driven from the power shaft 53 indicated in Fig. 1. Usually I provide a surface to support the leaf stems immediately underneath the cleaner; with the rotary form of cleaner described and illustrated, I find it preferable to make this support 54 (Fig. 3) arcuate, so as to hold the leaf stems in the paths of the cleaning members 47 for some little distance, as will be understood. 110 It will be understood of course that the blade material broken from the stems by this cleaner passes to the back of the machine, as indicated at 55 in Fig. 3. As will be apparent from Fig. 4 also, the wire-like members are preferably arranged in rows parallel with the axis of the hub 46; the number of rows is of no great concern; usually I use four rows equiangularly spaced circumferentially of the hub. Usually I space each two wire-like members 47 of a row, a distance 115 apart about equal to or a little less than the diameter of the average stem to be cleaned by the cleaner. As further illustrative of the matter, I might add that I have used for the cleaning members 47 rather stiff steel wires, each about 120 fifty one-thousandths of an inch in diameter.

125 While such a stem cleaner is quite adequate for stems that are somewhat separated from each other, it does not act with the highest efficiency when a number of stems are more or less intertwined together like the butt ends of the leaves shown at the left of Fig. 1. Such a limitation is found also in all prior stem butters of which I am aware. To enable the stem butting or cleaning to be carried on where the stems 130 approach the apparatus bunched or intertwined, I provide a comb, as it were, to comb out the intertwined stems, and lay the stems more or less parallel to each other and more or less separated from each other; the action will be 135 apparent by contrasting the stem butts shown at the left hand of Fig. 1 with those of the groups shown near the middle of Fig. 1. Preferably this comb also is rotary in form, and therefore may consist of a hub member 58 (Fig. 145 4), say of a rigid material, and a plurality of teeth 59 rigidly set in the hub, and sufficiently rigid to force their way between overlapping stems but sufficiently yielding to pass over hard foreign matter that may accompany the leaves, such as 150

- stones, pieces of wood, etc. Preferably the ends of the teeth 59 are slabbed at opposite sides, as will be apparent from Figs. 3 and 4, and preferably these teeth are somewhat bent backwards, as appears in Fig. 3. By way of example, I may say that for the teeth 59 I have employed stiff steel wires from three thirty-seconds to one-eighth of an inch in diameter each. Usually I arrange these wires in pairs, as illustrated in Fig. 4, and usually I use about four pairs around the circumference of the hub; the distance between the two wires of each pair I usually make a little greater than the diameter of the average stem to be worked on. The rotary comb 58—59
- 15 may be driven by sprocket wheel 60 and co-operating chain 61, also driven from the drive shaft 53. Usually I drive the comb and any co-operating butter or stem cleaner 46—47 separately, because usually it is not necessary to drive the
- 20 comb at such a high speed as the stem butter or stem cleaner; and this seems to be particularly true when the stem cleaner is such a one as that illustrated at 48, 49, 48. Underneath the comb, the stems are preferably supported, generally in the same manner as they are supported underneath the stem cleaner; that is to say, for example the curved member 54 may be extended to a position underneath the comb. Such a comb may be used wherever it is desirable to separate
- 25 stems bunched together, as will be understood. In working on the stems, it serves to break up any suckers so-called that may be present; it may indeed be used simply for the purpose of breaking up suckers, even when there is no need for it as a device for separating the stems. In co-operating with the stem cleaner before described, or any suitable form of "stem butter", it provides a device capable of properly cleaning stems presented to the cleaning device in a
- 30 more or less bunched and intertwined condition. Furthermore, together the comb and cleaner or butter constitute a stem-cleaning mechanism adapted to co-operate with a stemming machine having a feeder, or otherwise mechanism so arranged that it is adapted to receive the leaves to be stemmed in bunches.
- 35 It will be understood that my invention is not limited to the details of construction and operation illustrated in the accompanying drawing and described, except as appears hereinafter in the claims.
- 40 1. In a stem cleaning mechanism, a carrying body of substantially rigid material, a yielding member carried by said rigid material, a plurality of cleaning members carried by and projecting from said yielding member, and means to drive said carrying body to pass said cleaning members over stems presented to them, said means passing said cleaning members over the
- 45 stems in a direction substantially parallel to the stems.
- 50 2. In a stem cleaning mechanism, a plurality of cleaning members, carrying means for said cleaning members, the connection between said carrying means and said cleaning members normally holding said cleaning members projected substantially in cleaning position but being so yielding that at a speed somewhat less than normal said connection can yield sufficiently to permit said cleaning members to pass over the stems substantially without cleaning the latter, and means for moving said carrying member, to pass said cleaning members over the stems, at such a higher speed that the cleaning members
- 55 substantially clean the stems.
3. In a stem cleaning mechanism, a carrying body of substantially rigid material, a member projecting from the rigid material of said body, said member being flexible externally of the body of rigid material, a plurality of cleaning members projecting from said projecting member, said cleaning members being mounted entirely in a portion of said projecting member which is flexible externally of said rigid material, and means to drive said carrying body to pass said cleaning members over stems presented to them, said means passing said cleaning members over the stems in a direction substantially parallel to the stems.
- 80 4. In a stem cleaning mechanism, a rotatable carrying body of substantially rigid material, a plurality of members projecting from said body at different points around the periphery thereof, said members being flexible externally of the body of rigid material, a plurality of cleaning members projecting from said projecting members, said cleaning members being mounted entirely in portions of said projecting members that are flexible externally of said rigid material, and means to rotate said carrying body to pass said cleaning members over stems presented to them, said means rotating said body on an axis which extends substantially transversely across said stems.
- 85 5. In a stem cleaning mechanism, a hub member, a plurality of projecting cleaning members carried thereby, said cleaning members being distributed about said hub both circumferentially and axially of the hub, and the connection between each of said cleaning members and the hub normally holding said cleaning members projected substantially in cleaning position but being so yielding that at a speed somewhat less than normal said connections can yield sufficiently to permit said cleaning members to pass over the stems without substantial cleaning cooperation therewith, and means to rotate said hub at such a higher speed that the cleaning members substantially clean the stems.
- 90 6. In a stem cleaning mechanism, a hub member, a plurality of flexible members projecting spoke-like therefrom, a plurality of wire-like members projecting from said flexible members, the ends of said wire-like members nearer the hub axis being external of the periphery of the hub continued through said flexible members.
- 95 7. The combination of the subject matter of claim 2, with means providing a surface to support the stems within the paths of said cleaning members.
- 100 8. The combination with the subject matter of claim 4, of means providing a concave surface to support the stems within the path of the ends of said projecting members.
- 105 9. The combination with the subject matter of claim 5, of means providing a curved surface to support the stems within the path of the cleaning ends of said cleaning members.
- 110 10. In a leaf treating machine, a comb, means for supporting the stems of leaves, and means for moving said comb through the supported stems, characterized by the fact that the teeth of said comb are bent backwards.
- 115 11. In a leaf treating machine, a hub member, a plurality of members projecting spoke-like therefrom, said members being distributed about the hub both circumferentially and axially of the hub, and said members being sufficiently rigid, and sufficiently rigidly mounted in said hub, to pass between and separate overlapping leaf stems
- 120 125 130 135 140 145 150

- when said hub is rotated, but sufficiently yielding to pass over hard matter without breaking and means for rotating the hub.
12. The combination with the subject matter of claim 11, of means to support leaf stems in the paths of said projecting members.
13. The subject matter of claim 11, characterized by the fact that said projecting members are arranged in a plurality of rows, each row extending substantially parallel with the axis of the hub.
14. In a leaf treating machine, the combination of a comb, means to move the comb through the leaf stems, and means to the rear of said comb to clean the portions of the stems operated on by said comb.
15. In a leaf treating machine, the combination of a rotary comb, means to rotate said comb to separate the leaf stems, a rotatable carrying body of substantially rigid material to the rear of said comb, a plurality of members projecting
- from said body at different points around the periphery thereof, said members being flexible externally of the body of rigid material, a plurality of cleaning members projecting from said projecting members, said cleaning members being mounted entirely in portions of said projecting members that are flexible externally of said rigid material, and means to rotate said carrying body to pass said cleaning members over stems presented to them.
16. The combination with a stemming machine including a mechanism adapted to receive leaves in bunches, of a comb, means to move the comb through the butt ends of the leaf stems to separate the same, and means to the rear of said comb to clean said butt ends, said comb and the last mentioned means being located adjacent a portion of said mechanism wherein the leaves are in bunches and operating on leaves carried by the said mechanism.
